ROUND BALE FORMING MACHINE

Melvin Victor Gaeddert, Newton, and Bobby Dwayne
McWhirt, Hesston, Kans., assignors to Hesston Corpora-
tion, Hesston, Kans.

Filed Oct. 4, 1974, Ser. No. 511,733

Term of patent 14 years

Int. Cl. D15—03

U.S. Cl. D40—1 E

Fig. 1.

Fig. 2.

Fig. 4.

Fig. 5.

Fig. 6.

FIG. 1 is a top, left, front perspective view of a round bale forming machine showing our new design;

FIG. 2 is a front perspective view thereof.

FIG. 3 is a perspective view showing the left side thereof;

FIG. 4 is a perspective view showing the right side thereof;

FIG. 5 is a perspective view showing the top, rear and right side thereof; and

FIG. 6 is a perspective view showing the rear end thereof.

We claim:

The ornamental design for a round bale forming machine, as shown.
